UNITED STATES PATENT OFFICE.

JOHN R. BARRETT, OF CHICAGO, ILLINOIS.

TEMPORARY BINDER.

SPECIFICATION forming part of Letters Patent No. 774,550, dated November 8, 1904.

Application filed May 31, 1902. Serial No. 109,713. (No model.)

To all whom it may concern:

Be it known that I, JOHN R. BARRETT, a citizen of the United States, residing at Chicago, in the county of Cook and State of Illinois, 5 have invented certain new and useful Improvements in Temporary Binders, of which the following is a specification, reference being had to the accompanying drawings.

My invention relates to temporary binders, 10 and has particularly to do with binders of what are known as the "Emerson" type. As is well understood, in binders of that type the periodicals or other papers placed in the binder are secured between binder-strips carried by the back, the papers being secured by cords passing through them and through the binder-strips, the ends of the cords being secured to cleats usually carried by one of said strips. A binder of this type is illustrated 15 and described in my application, Serial No. 655,053, filed October 13, 1897.

My present invention has specially to do with the construction of the cleats and the manner of securing the same to the binder-strips or to such other part of the binder as they may be attached to.

It has for its object to provide an improved construction by which the cleats are firmly secured in place and by which a more efficient 20 and desirable construction is secured.

What I regard as new is set forth in the claims.

In the drawings, Figure 1 is a partial plan view of a binder, showing the intermediate 25 portions of the covers and the parts connected thereto. Fig. 2 is a cross-section on line 2 2 of Fig. 1. Fig. 3 is an enlarged detail, being a view of a portion of one of the binder-strips, showing the cleat in plan. Fig. 4 is a 30 sectional view on line 4 4 of Fig. 3, and Fig. 5 is a perspective view showing a modification.

Referring to the drawings, 6 7 indicate the covers, which, as shown in Fig. 2, are connected by the usual flexible connection 8, 45 which forms the back of the binder.

9 10 indicate the binder-strips, which are preferably secured to the covers 6 7 by cloth, canvas, or other suitable material 11, which incloses them and connects them to the covers,

as shown. By this construction the strips 9 50 10 are flexibly connected to the covers.

In the construction shown in Fig. 1 the binder-strip 9 is perforated to receive the cords 12, which secure the contents of the binder in place. The arrangement of cords 55 shown in Fig. 1 is fully illustrated and described in my former application above referred to and is here illustrated, because it is an efficient arrangement. I wish it to be understood, however, that the binder-strips may 60 be arranged for a single cord, if desired, in the manner shown in my application, Serial No. 702,483, filed January 17, 1899, or in any other suitable manner.

The strip 10 in the construction illustrated 65 is shown as carrying the cleats to which the ends of the cords are secured. In the drawings I have shown two forms of cleats embodying my improvements, the preferred form being shown in Figs. 1, 2, 3, and 4. 70 Referring to said figures, 13 indicates the cleat, which is formed of a piece of wire doubled upon itself at its ends, the central portion of the wire being spread so as to form a substantially annular passage 14 at the center 75 of the cleat. The end portions 15 16 form arms which, as shown in Fig. 4, are bent upward and outward, so that when the cleat is in place they lie over and adjacent to the surface of the strip 10, as shown in Fig. 4. The arrangement is such that the end of the cord may be looped around or belayed upon the arms 15 16 of the cleat, and when so belayed the elasticity of the arms serves to hold the cord tightly in place. As best shown in Fig. 4, the 85 central annular portion of the cleat lies below the strip 10, while the arms 15 16 project through it and lie over and adjacent to the upper surface thereof. The strip 10 is perforated in line with the annular opening 14 in 90 the cleat, as shown in Fig. 3, so that the cord may be passed through the cleat and strip in the manner illustrated in Fig. 1. This arrangement of the cleat in connection with the strip forms another of the principal features of my present invention.

For securing the cleat in place I provide an eyelet 17, having a flange 18 at one end, a flange 19 being

formed at the other end by pressing or turning out the projecting end of the eyelet, as shown in Figs. 3 and 4. If desired, an annular disk 20 may be placed between the flange 18 and 5 the adjacent part of the cleat to provide a broader bearing upon the cleat to hold it more firmly in place. By this construction the arms 15 16 of the cleat are strengthened and the cleat as a whole is secured much more 10 firmly in place than where it is secured entirely upon the upper surface of the strip, as has heretofore been the practice. Furthermore, a neater appearance is presented.

In Fig. 5 I have illustrated a cleat 21, similar to the cleat 13 so far as the shape is concerned, differing therefrom, however, in being formed of a flat piece of metal instead of a wire bent to the desired shape. My invention, broadly considered, includes the form of cleat 20 shown in Fig. 5, as well as that shown in the other figures.

Regarding the wire cleat shown in the first four figures, I wish it to be understood that so far as the cleat *per se* is concerned my invention is not restricted to using a wire cleat having the construction described solely in the manner shown in said figures, as, if desired, it may be arranged to be attached to the upper surface of the binding-strip after the manner 25 illustrated in my former application, Serial No. 655,053, filed October 13, 1897.

That which I claim as my invention, and desire to secure by Letters Patent, is—

1. In a binder, the combination of a supporting-strip, a cleat consisting of an intermediate portion and arms extending therefrom, the intermediate portion of the cleat being secured at one side of said strip and the arms thereof being projected through said strip and extending

over the opposite face of said strip, and a passage through said strip and cleat, substantially as described. 40

2. In a binder, the combination of a supporting-strip, a cleat consisting of an intermediate portion and arms extending therefrom, the inner portions of said arms being fitted into said strip, and a passage through said strip and intermediate portion of the cleat, substantially as described. 45

3. In a binder, the combination of a supporting-strip, a cleat consisting of intermediate portions and arms extending therefrom, the intermediate portion of the cleat being secured at one side of said strip and the arms being arranged to project over the opposite face of 55 said strip, and an eyelet securing the intermediate portion of said cleat to said strip, substantially as described.

4. In a binder, the combination of a supporting-strip having an intermediate passage, a 60 lateral passage at opposite sides of said intermediate passage, a cleat having an intermediate portion adapted to fit against one face of said strip and to lie over said intermediate passage, said cleat having projecting arms 65 adapted to fit in said lateral passage and to project over and adjacent to the opposite face of said strip, substantially as described.

5. A cleat for binders, composed of a wire doubled upon itself and bent to form upwardly 70 and outwardly projecting arms, the intermediate portions thereof being spread laterally to form a central passage, substantially as described.

JOHN R. BARRETT.
